United States Patent Office

Des. 227,945
Patented July 24, 1973

227,945

LADIES PURSE

Gertrude B. Hirtz, 420 Monroe Ave.,
Campbell, Mo. 63933

Filed June 28, 1971, Ser. No. 157,802

Term of patent 14 years

Int. Cl. D3—01

U.S. Cl. D87—3 F

FIG. 1

FIG. 2

FIG. 3

FIG. 4

FIG. 5

FIG. 1 is a front elevational view of a ladies purse, showing my new design.

FIG. 2 is an end elevational view, the opposite end being substantially similar thereto.

FIG. 3 is a top plan view thereof.

FIG. 4 is a back elevational view thereof.

FIG. 5 is a bottom view thereof.

I claim:

The ornamental design for a ladies purse, as shown and described.
